UNITED STATES PATENT OFFICE

EARLE CHAPMAN PEART, OF LOWELL, MASSACHUSETTS

HEEL STAINER

Application filed September 8, 1931. Serial No. 561,753.

The invention relates to a heel trimming machine attachment and more especially to a heel stainer.

The primary object of the invention is the provision of an attachment of this character wherein staining liquid can be conveyed to the beveled edge of the top lift of a heel of a woman's shoe so that such edge can be stained simultaneously with the trimming thereof, the attachment being of novel form so as to follow and properly stain the top lift of the heel during the working of the trimming machine.

Another object of the invention is the provision of an attachment of this character which is extremely simple in construction, thoroughly reliable and efficient in its operation, readily and easily attached to and operative with a wood heel trimming machine, automatic in the working thereof, and inexpensive to manufacture and install.

With these and other objects in view, the invention consists in the features of construction, combination and arrangement of parts as will be hereinafter more fully described in detail, illustrated in the accompanying drawings, which disclose the preferred embodiment of the invention, and pointed out in the claims hereunto appended.

20 In the drawings:—

Figure 1 is a fragmentary elevation of a shoe heel trimming machine showing the attachment constructed in accordance with the invention applied thereto.

25 Figure 2 is an end elevation partly in section.

Figure 3 is a horizontal sectional view.

Figure 4 is a detail elevation of a staining brush assembly.

30 Figure 5 is an end elevation thereof.

Figure 6 is a bottom plan.

Figure 7 is a side elevation.

Figure 8 is a sectional view on the line 8—8 of Figure 7.

45 Similar reference characters indicate corresponding parts throughout the several views in the drawings.

Referring to the drawings in detail, A designates the head of a wood heel trimming machine which may be of any standard

construction and is equipped with the usual toothed trimming knife B, its journal being driven in any suitable manner preferably by a belt (not shown). The knife is covered by a guard C so that only the working portion thereof is exposed for action upon the top lift D of a heel E of a shoe of the women's type. Adjustably confronting the working portion of the wheel B is a face plate F, the latter being vertically disposed and against which the top lift D rests when the knife B is active thereon for the trimming of such lift by the knife.

On the head A of the machine is an upright 10 carrying at its upper end a container 11 for liquid staining and from the bottom of said container leads a feed tube 12, the latter being connected with a curved brush stock 13 carrying a brush tip 14, the latter being preferably made from rubber and is fastened in place through the medium of a set screw 15, the tip 14 being formed with an applicator tongue 16 onto which is delivered the liquid staining from a feed passage 17, the latter communicative through the port 18 with the stock 13 and this tongue 16 plays against the trimmed edge 19 of the top lift D of the heel E subsequent to the trimming thereof by the knife B so that during the trimming operation of said top lift its trimmed edge 19 will be stained in a manner as will be understandable from Figures 1, 2 and 3 of the drawings.

The top lift D of the heel E is brought into position to rest against the face plate F, see Figure 1, immediately beneath the knife B and the working of this wheel causes the trimming of the top lift D when the latter is brought into the path thereof and this trimming is continued by the turning of the heel upon the face plate F. Simultaneously with this operation the applicator tongue 16 which carries liquid staining will apply the latter to the trimmed top lift D of the heel.

Immediately beneath the tongue 16 is a trap 20 for catching all drippings and excess liquid staining during the operation of the beveling and trimming machine.

The stock 13 which forms the feed throat

from the feed pipe 12 has its flow regulated by a regulating valve 21 to control the feed of the liquid staining from the container 11 therefor. This container 11 has a removable cover or lid 22.

It is contemplated within the scope of the present invention to employ a pump attached to the trap, the pump being not shown so that the drippings received by the trap can be forced back to the original container for the stainer.

What is claimed is:—

1. The combination with a heel trimming machine having a trimming knife, of an attachment comprising a container for liquid staining, a support for the container and carried by the machine, means arranged in juxtaposition to the knife for delivering the liquid staining to the top lift of a heel when trimmed by the knife, means for delivering the liquid staining from the container to said first named means, means for regulating the flow of the liquid staining to the first named means, and a trap located beneath said first named means for catching drippings of liquid staining from said first named means.

2. The combination with a heel trimming machine having a trimming knife, of an attachment comprising a container for liquid staining, a support for the container and carried by the machine, means arranged in juxtaposition to the knife for delivering the liquid staining to the top lift of a heel when trimmed by the knife, means for delivering the liquid staining from the container to said first named means, means for regulating the flow of the liquid staining to the first named means, a trap located beneath said first named means for catching drippings of liquid staining from first named means, and a flexible applicator tongue associated with the first named means and engageable with the heel lift at its edge.

In testimony whereof I affix my signature.

EARLE CHAPMAN PEART.
